UNITED STATES PATENT OFFICE.

PEARL R. WOOLF, OF OKLAHOMA CITY, OKLAHOMA.

COLLAPSIBLE BUCKET.

Application filed April 3, 1926. Serial No. 99,645.

This invention relates to collapsible or foldable buckets and the general object of my invention is to provide a bucket of paraffined or waxed paper or other light and 5 readily foldable fabric, which is designed to be used where liquids are transported for a short distance and which is capable of use for transporting gasoline and oils from a filling station to a stranded car or for carrying 10 liquids or other materials from one place to another.

A further object is to provide a bucket which, as before remarked, is made of paraffined paper and which may be folded into 15 very compact form so that a number of these buckets can be readily shipped by parcel post at very small cost and so that a number of buckets may be readily carried in a car when touring.

20 Another object is to provide a bucket of this character which is conical or has the form of a cornucopia and which, being made of paper, may have its pointed end torn off so that the bucket may be used as a funnel 25 on occasion.

A still further object is to provide a bail for the bucket of a very light character which may be utilized with a number of different buckets if desired, and so form the 30 bucket that the bail may engage at a plurality of points with reenforced portions on the bucket.

Other objects will appear in the course of the following description.

35 My invention is illustrated in the accompanying drawings wherein:—

Figure 1 is a perspective view of a bucket constructed in accordance with my invention, the lower portion of the bucket being 40 folded;

Fig. 2 is a vertical sectional view of the upper portion of the bucket showing the top folded in;

Fig. 3 is an elevation of the bucket;

45 Fig. 4 is a section on the line 4—4 of Figure 3;

Fig. 5 is a fragmentary section on the line 5—5 of Figure 3;

Fig. 6 is a view of the bucket in its fully 50 folded condition.

Referring to these drawings it will be seen that the body 10 of the bucket is conical in form, or as before remarked, has the form of a cornucopia, and this body is formed 55 of relatively heavy paper which has been waxed or paraffined so that it will carry

liquids. This body may be made in any suitable manner and may be made of any suitable size, a convenient size being about 2' long and 1' in diameter. 60

The upper margin of the bucket is formed at a plurality of points with reenforced portions through which the ends of a bail may pass. As illustrated, each reenforced portion is formed by cutting out a semi-circular 65 ear 11 from the body of the bucket and turning this ear over upon the outside face of the bucket and pasting it or gluing it in place. A perforation 12 is then formed through the body of the bucket and through the re-enforced portion constituted by this ear. 70

The bail is preferably formed of relatively heavy and stiff wire and bent to form an approximately U-shaped handle 13, the wire being laterally extended at one end, as 75 at 14, and then returned upon itself and again laterally extended beyond the bail, as at 15. The ends of the portions 14 and 15 are angularly bent as at 16, so as to form hooks adapted to extend through the perforations 12. Both ends of the bail are 80 formed in the same manner. Thus the bail consists of a handle portion and two laterally and downwardly directed arms, the extremities of the arms being hooked. 85

This bucket may be folded, as illustrated in Figure 6 so that the lower portion of the conical bucket will be parallel along one side edge of the upper portion of the bucket, the paper of the bucket being, of course, 90 flattened down and the bail being bent so as to lie in a parallel plane. Thus, a number of these buckets folded as described may be packed together for transportation and will take up very little room. 95

The opposed walls of the paper cone at the extreme tip of the cone may be pasted together and a hole 17 made through these two layers or thicknesses and when the bucket is folded, one of the hooks of the bail 100 may pass through these perforations so that the bail acts to hold the bucket in its folded position.

The use of this bucket will be obvious and it will be seen that inasmuch as the reenforced portions 11 are formed below the upper margin of the paper constituting the bucket, this upper margin may be turned inward or down inside of the bucket to constitute a lid which will at least prevent the splashing out of the contents of the bucket. 105 If it be desired to use the bucket for a fun- 110

nel the tip end of the bucket is torn away on the dotted line 18 and obviously this tear may be made nearer to or further from the hole 17 so as to make a relatively small 5 or a relatively large discharge opening for the funnel so formed.

The top of the bucket is formed with 10 longitudinally extending slots or cuts 19 to permit the folding in of the top of the bucket to form the lid as shown in Figure 2, and also the slots are cut to give room for the bail and to lap when turned inside. Of course, the bucket shown in Figure 1 need 15 not have its tapered end turned up as illustrated, but this makes the bucket shorter, stronger, and easier to handle.

I claim:—

A collapsible bucket of the character described having a conical body formed of

water-proof paper, the body being adapted 20 to be folded upon itself and flattened for transportation, the body at four points being cut away in a semi-circle to form ears which are bent downward upon the body, a 25 U-shaped bail, the extremities of the bail being extended laterally in opposite directions to provide two parallel portions, the parallel portions at their extremities extending through the body and through said ears and said extremities being upwardly turned 30 to form hooks, the transversely extending parallel portions of the bail acting to hold the mouth of the bucket in a distended condition.

In testimony whereof I hereunto affix my 35 signature.

PEARL R. WOOLF.
